UNITED STATES PATENT OFFICE.

FRANK MORTON, OF MUSKOGEE, OKLAHOMA.

VENTILATING STORAGE BIN.

Application filed December 2, 1921. Serial No. 519,565.

To all whom it may concern:

Be it known that I, FRANK MORTON, a citizen of the United States, residing at Muskogee, in the county of Muskogee and 5 State of Oklahoma, have invented new and useful Improvements in Ventilating Storage Bins, of which the following is a specification.

This invention relates to bins for the 10 storage of grain and has for its object the provision of a novel bin which is so constructed as to permit thorough ventilation of the grain without it being necessary to transfer the grain from one point to another at 15 intervals as is the ordinary practice.

It is well known that the storage of grain 20 has always been with risks and more or less loss, owing to the tendency of the grain to heat while in the bins. The ordinary method of treatment is by transferring the grain from one bin to another at certain 25 intervals of time whereby to effect ventilation, but this method has several disadvantages the principal one of which is that transferring does not properly cool the grain 30 and another of which is the chipping of the grain which always causes considerable loss.

Unless the grain is ventilated by some 35 means it will naturally eventually deteriorate so as to be rendered useless for food purposes. Grain in this unventilated condition also develops weevils and this is another source of great loss. The ordinary method of transferring the grain from bin 40 to bin requires the expenditure of a great amount of time and labor and is an expensive operation as it requires the services of workmen and involves a great deal of wear and tear on the necessary machinery together with the expense of the fuel for driving 45 the machinery. Furthermore such transfer involves the giving off of vast clouds of dust which are very deleterious to the health of the workmen employed in and around the elevator. This is known as "mill dust" and frequently causes explosions and spontaneous combustion. Furthermore 50 empty bins must always be reserved so as to be available for purposes of transfer as will be of course understood. It is with the above mentioned objects and conditions in view that the present invention has been designed.

The essential object of the present invention 55 is the provision of a bin of novel construction and with which is associated a

suitable blower whereby larger quantities of air under pressure may be forced through the entire bin for the purpose of removing the foul air therein and cooling as well as 60 drying the grain.

An additional object is the provision of a bin of this character which will be simple and inexpensive in construction, highly efficient in use, durable in service and a 65 material improvement.

With the above and other objects and advantages in view, the invention consists in the details of construction to be hereinafter more fully described and claimed, and illustrated in the accompanying drawings in 70 which:—

Figure 1 is a longitudinal sectional view through a bin constructed in accordance 75 with my invention.

Figure 2 is a cross sectional view there- 75 through showing the rectangular top.

Figure 3 is a cross sectional view of a modified form showing a circular or cylind- 80 rical top.

Referring more particularly to the drawings I have shown the bin 10 as having a lower or outer hopper-shaped bottom 11 pro- 85 vided centrally with an opening 12 for the discharge of grain, this opening being nor- mally closed by the usual sliding gate 13. Secured within the bin in parallel relation and above the bottom 11 is a hopper-shaped member or false bottom 14 which is likewise 90 formed at its center with a discharge open- 95 ing 15 which is never closed. As the bin is filled with grain every space within the bin is occupied with grain except the space be- 100 tween the lower bottom 11 and the upper bottom 14. This space extending all around the bin is a spacious air chamber 16 into which the grain never enters and with which it does not interfere.

Entering into this air chamber 16 at some point near the top is a pipe 17 through which air is forced from any suitable blower 18 which may be driven by any preferred means.

In Figures 1 and 2 I have shown the bin as being rectangular in cross section while in Figure 3 I have shown it as being circular in cross section and it will be understood that the shape makes no difference whatever.

Assuming that the bin is full of grain, 110 whenever it is desired to ventilate the grain it is merely necessary to operate the blower

18 whereupon air will be forced under pressure into the space 16 and through the opening 15 up into and through all the grain in the bin. It is well known that grain in a bin is 5 not a compact body and that there is a small space between all of the individual kernels which will readily permit such air under pressure to pass through the entire mass so that every kernel will be subjected to the 10 action of the air for the purpose of effecting cooling and drying so that in this way the entire contents of the bin may be kept in a thoroughly satisfactory condition which will insure keeping of the grain for a long period 15 of time.

From the foregoing description and a study of the drawings it will be apparent that I have thus provided a bin of very simple construction which may be very readily ventilated and which will insure the saving not only of grain but also expenditure of time and money as well as labor in the proper treatment of the grain.

While I have shown and described the 25 preferred embodiment of the invention it is of course to be understood that I reserve the right to make such changes in the form, construction and arrangement of parts as will not depart from the spirit of the in-

vention or the scope of the subjoined claims. 30

Having described the invention I claim:—

1. A bin comprising an elongated hollow body arranged in upright position and having a hopper-like bottom provided with a normally closed discharge opening, a false 35 bottom within the lower portion of the body spaced from the hopper-like bottom to define a continuous air space, said false bottom being formed with an opening of greater size than the discharge opening at the bottom of the body, and means for forcing compressed air into said continuous air space.

2. A bin comprising an upright hollow body, a hopper-shaped bottom therefor having a normally closed outlet opening, a false bottom located above and in spaced parallel relation to said first named bottom and likewise formed with a discharge opening registering with said first named opening, a pipe leading through said first named bottom near one outer edge thereof and communicating with the space between the two bottoms, and means for forcing air under pressure through said pipe. 45

In testimony whereof I affix my signature.

FRANK MORTON.
